UNITED STATES PATENT OFFICE.

ADA MAE SIMPSON, OF EATON RAPIDS, MICHIGAN, ASSIGNOR TO EATON RAPIDS WOOLEN MILLS, OF EATON RAPIDS, MICHIGAN, A CORPORATION OF MICHIGAN.

FRESH-AIR GARMENT.

Application filed October 22, 1923. Serial No. 670,059.

This invention relates to garments of a type worn in "open air schools," the object of the present invention being to provide an overgarment of this type having certain 5 novel and advantageous features hereinafter set forth.

In the attached drawings:

Figure 1, illustrates the garment as worn; Fig. 2, is a front view of the upper or 10 jacket portion of the garment with the bib portion down, and

Fig. 3, is a front view of the garment including the trousers with the bib portion of the jacket secured to place at the neck.

15 With reference to the drawings, the garment, which preferably is of wool and of such weight as to afford ample protection as an overgarment, comprises a jacket portion 1 and separable trousers 2. The trousers 2 are of the usual form and preferably of such 20 length as to permit their being tucked into the top of woolen stockings, as clearly illustrated in Fig. 1.

The upper or jacket portion 1 of the garment comprises a hood 3 adapted to be tied 25 at the neck by a cord or tape 4. The body of the jacket is divided at the front from the neck to a point 5 somewhat above the bottom edge of the jacket, and the parts are 30 held together at the neck by the aforesaid tape 4.

Extending across the bottom of the jacket at the front and secured to the garment along the lower edge 6 and the side edges 7, 35 7, is a piece of material 8, preferably the same as the material from which the body of the jacket is made, said piece comprising an elongated flap 9 which extends from the upper edge of the piece 8 and is provided

with means such as tapes 11 for securing 40 the outer end at the neck of the garment. The piece 8 with its flap 9 accordingly constitutes in effect a bib which, secured at the neck, extends down the front of the garment and overlies the front opening. The 45 piece 8 is also secured to the body of the garment by a perpendicular line of stitches 12 which divides the lower part of the pocket formed by the piece 8 into halves into which the hands of the pupil may be stuffed, 50 as indicated in Fig. 1.

The flap 9 of the piece 8, as will be apparent, not only affords double protection at the front of the garment but also provides a double security at the neck, while the lower 55 part of the bib portion 8—9 constitutes pockets.

As clearly illustrated, the garment, when the tapes 4 are untied, is open at the front from the tip of the hood to the point 5 near 60 the bottom of the garment, making the garment an extremely easy one to put on and remove. The garment, also, while an efficient one is extremely simple to manufacture.

I claim:

A garment comprising a jacket open at the front from the neck to a point short of the bottom edge of the jacket, a piece of material extending across the front and bottom of the jacket and secured at the side edges and bottom to form a pocket, said piece being secured at the center to the body of the garment whereby the said pocket is divided, and a flap extending from the said piece upwardly and around the neck of the garment.

ADA MAE SIMPSON.
